UNITED STATES PATENT OFFICE.

LOUIS MELCHER, OF NEW YORK, N. Y.

DESIGN FOR A POURING-GUIDE.

SPECIFICATION forming part of Design No. 30,235, dated February 21, 1899.

Application filed December 27, 1898. Serial No. 700,462. Term of patent 7 years.

To all whom it may concern:

Be it known that I, LOUIS MELCHER, a citizen of the United States, and a resident of the borough of Manhattan, in the city of New York and State of New York, have invented a certain new, useful, and original Design for Pouring-Guides, of which the following is a specification, reference being had to the accompanying drawings, which form part of the same.

The invention relates to a design for pouring-guides; and it consists in the novel configuration and shape herein shown and claimed.

In the accompanying drawings, Figure 1 is a plan view of a pouring-guide embodying my new design, also indicating by broken lines its application to a box or drawer. Fig. 2 is

a side elevation of the pouring-guide looking in the direction indicated by the arrow 2, Fig. 20 1, and Fig. 3 is a side elevation thereof looking in the direction of the arrow 3, Fig. 1.

The characteristic feature of my design consists in the configuration and shape of the pouring-guide shown, comprising the medial 25 inclined surface *a*, the side grooves *b b*, and the raised flat sides *c c*.

What I claim, and desire to secure by Letters Patent, is—

The design for a pouring-guide, substantially as shown and described.

Signed this 24th day of December, 1898.

LOUIS MELCHER.
